CLAIM

The ornamental design for an electric motor, as shown and described.

DESCRIPTION

FIG. 1 is a perspective view, taken from the front and left, of the electric motor of the present invention;

FIG. 2 is a perspective view, taken from the front and right, of the electric motor shown in FIG. 1;

FIG. 3 is a perspective view, taken from the rear and right, of the electric motor shown in FIG. 1;

FIG. 4 is a perspective view, taken from the rear and left, of the electric motor shown in FIG. 1;

FIG. 5 is a front view of the electric motor shown in FIG. 1; FIG. 6 is a left side view of the electric motor shown in FIG. 1; and,

FIG. 7 is a right side view of the electric motor shown in FIG. 1.

The broken lines in FIGS. 1-4, 6 and 7 illustrate portions of the electric motor that form no part of the claimed design.
